DISPOSABLE GRASS CATCHER BAG

Victor Leader, Rte. 1, Box 56D, Cedar, Minn. 55011

Filed June 30, 1971, Ser. No. 158,653

Term of patent 14 years

Int. Cl. D15—03, 99
U.S. Cl. D40—1 A

FIG. 1

FIG. 2

FIG. 3

FIG. 4

FIG. 5

FIG. 1 is a flat side view of the disposable grass catcher bag showing my new design;

FIG. 2 is a top plan view of the expanded disposable grass catcher bag of FIG. 1;

FIG. 3 is a front elevational view of FIG. 2;

FIG. 4 is a rear elevational view of FIG. 2; and

FIG. 5 is a sectional view taken along line 5—5 of

FIG. 2.

I claim:

The ornamental design for a disposable grass catcher bag, substantially as shown and described.
